Primary Examiner — Karen S Acker(74) *Attorney, Agent, or Firm* — Reinhart Boerner Van Deuren s.c.(57) **CLAIM**

The ornamental design for a toilet tissue with raised pattern, as shown and described.

DESCRIPTION

FIG. 1 is an isometric view of the toilet tissue with raised pattern from the front, bottom and left side;

FIG. 2 is a front plan view thereof;

FIG. 3 is a partial cross-sectional view taken along line 3-3 in FIG. 2;

FIG. 4 is a partial cross-sectional view taken along line 4-4 in FIG. 2;

FIG. 5 is a back plan view of the toilet tissue with raised pattern of FIGS. 1 and 2;

FIG. 6 is a top side view of the toilet tissue with raised pattern of FIG. 2;

FIG. 7 is a bottom side view of the toilet tissue with raised pattern of FIG. 2;

FIG. 8 is a right side view of the toilet tissue with raised pattern of FIG. 2; and,

FIG. 9 is a left side view of the toilet tissue with raised pattern of FIG. 2.

The dash dot dash broken lines surrounding the toilet tissue with raised pattern shown in FIGS. 1 and 2 depict the boundaries of the claim and form no part thereof. The depth of the toilet tissue with raised pattern beyond the top surface and the back surface of the article illustrated in dash dot dot dash broken lines represent portions of the toilet tissue with raised pattern that are not included in the claim. All broken lines form no part of the claimed design.
